(57) **CLAIM**

The ornamental design for a candy bar wishing well, as shown and described.

DESCRIPTION

FIG. 1 is a top, front, right side perspective view of a candy bar wishing well embodying my design;

FIG. 2 is a front elevational view thereof, the rear elevational view being a mirror image thereof;

FIG. 3 is a cross sectional view taken along line 3—3 of FIG. 2, and showing the underside of the roof;

FIG. 4 is a cross sectional view taken along line 4—4 of FIG. 2, and showing the top of the well;

FIG. 5 is a top plan view thereof;

FIG. 6 is a bottom plan view thereof; and,

FIG. 7 is a left side elevational view thereof.
